UNITED STATES PATENT OFFICE.

WILLIAM W. WOLFF AND LOUIS WOLFF, OF SHEBOYGAN, WISCONSIN.

CHAIR-IRON.

1,263,502.

Specification of Letters Patent. Patented Apr. 23, 1918.

Application filed December 21, 1916. Serial No. 138,141.

To all whom it may concern:

Be it known that we, WILLIAM W. WOLFF and LOUIS WOLFF, citizens of the United States, and residents of Sheboygan, in the county of Sheboygan and State of Wisconsin, have invented new and useful Improvements in Chair-Irons, of which the following is a description, reference being had to the accompanying drawings, which are a part of this specification.

The invention relates to chair irons.

The invention is more particularly designed to provide means for readily adjusting the height of the revoluble spindle of the chair.

The invention consists in the several features hereinafter set forth and more particularly defined by claims at the conclusion hereof.

20 In the drawings:

Figure 1 is a vertical sectional view of the device embodying the invention;

Fig. 2 is a section taken on the line 2—2 of Fig. 1;

25 Fig. 3 is a section taken on the line 3—3 of Fig. 1.

In the drawings, the numeral 4 is the hub of the iron and is usually made of metal, provided with sockets for receiving the 30 chair legs. This hub is provided with a vertically extending smooth cylindrical bore 5.

A cylindrical sleeve 6 is slidably mounted in the bore 5, rotation of the sleeve with respect to the hub 4 being prevented by 35 means of a set-screw 7 engaging in a key-way slot 8 in the sleeve. The sleeve 6 is provided with a vertically extending cylindrical bore 9.

The numeral 10 represents the base portion of the chair, to which a spindle 11 is connected, said spindle being revolvably mounted within the cylindrical bore 9 of the sleeve 6 and being held therein through the washer 12 at the lower end of the sleeve 45 6 held in place by means of a pin 13 passing through said spindle and engaging said washer.

The general combination of hub, spindle and sleeve are old and well-known, but the 50 present invention is directed to the means for elevating or depressing the chair without interfering with the rotary movement of the chair with respect to the hub of the iron.

This is accomplished by providing means 55 for removably locking the sleeve 6 to the

hub 4 in different positions of vertical adjustment.

This means consists of a dog 14 which is slidably mounted in a slot 14' in the hub 4 and whose end 15 is adapted to engage in any one of a plurality of notches 16 formed in the sleeve 6, and means are provided for operating said dog. This means consists of a vertically disposed lever 17 slidably mounted in an aperture 18 in the hub 4 and having a connection with said dog and having an outwardly extending pedal portion 19. The rod 17 is connected up to operate the dog 14 through a cam connection consisting of a downwardly inclined slot 20 in the rod 17 in which a pin 21, carried by the bifurcated arms 22 of the dog 14, is slidably mounted. A coiled spring 23 is mounted on the rod 17 between the dog 14 and a collar 24 held in place on the rod by a pin 25.

With this construction when the operator desires to elevate or depress the chair he presses his foot on the pedal 19 of the rod 17, thus moving said rod downwardly and thus through the slot and pin connection 20 and 21 moving the dog 14 outwardly in the slot 14' to move it out from engagement with the notch 16, after which he may move the sleeve to the height desired and release the rod 17, thereby allowing the compressed spring 23 to move the rod 17 upwardly and return the dog 14 to locking engagement with the desired notch 16 in the sleeve member 6, and as the spindle 11 is connected to the sleeve it will also be raised and lowered with said sleeve and will be free to rotate therein.

The invention thus exemplifies a simple and efficient construction for accomplishing the purpose desired.

What we claim as our invention is:

1. In a chair iron, the combination of a hub member, a sleeve member vertically slidably mounted within said hub member, a spindle journaled in said sleeve, and means for securing the spindle and sleeve in different positions of vertical adjustment comprising a dog slidably mounted in the hub member and adapted to engage the sleeve member, said hub member having a bore therein adjacent said sleeve, a rod vertically slidably mounted within said bore and having a pedal portion extending outwardly from the hub member, said rod being connected with said dog to release the same.

from locking engagement with said sleeve member on the depression of rod, and means for returning the rod and dog to normal locking position.

5. 2. In a chair iron, the combination of a hub member provided with a pair of vertically extending bores and a slot extending between said bores intermediate their ends, a sleeve member non-rotatably but vertically 10 slidably mounted in one of said bores, a spindle journaled in and carried by said sleeve, a rod vertically slidably mounted in

the other bore and having a pedal portion extending outwardly from the bottom of the hub member, a dog slidably mounted in said 15 slot and adapted to engage the sleeve member, and a connection between said dog and rod to release said dog from said sleeve member on a depression of said rod.

In testimony whereof, we affix our signatures. 20

WM. W. WOLFF.
LOUIS WOLFF.
